(57) **CLAIM**

The ornamental design for an arched potted-plant holder, as shown and described.

DESCRIPTION

FIG. 1 is a front perspective view of an arched potted-plant holder showing my new design.

FIG. 2 is a top plan view thereof.

FIG. 3 is a right side elevational view thereof.

FIG. 4 is a front elevational view thereof.

FIG. 5 is a left side elevational view thereof.

FIG. 6 is a rear elevational view thereof.

FIG. 7 is a bottom plan view thereof; and,

FIG. 8 is a front elevational view of an arched potted-plant holder that is holding seven pots and is mounted to a wall in front of a window.

The broken line showing in FIG. 8 is for illustrative purposes only and forms no part of the claimed design.
